(57) CLAIM

I claim the ornamental design for a cosmetics brush, as shown and described.

DESCRIPTION

FIG. 1 is a perspective view of a cosmetics brush embodying the invention;

FIG. 2 is a front view of the cosmetics brush of FIG. 1; FIG. 3 is a left side view of the cosmetics brush of FIG. 1; and,

FIG. 4 is a top view of the cosmetics brush of FIG. 1. The broken lines showing the bristles are included for the purpose of illustrating portions of the cosmetic brush that form no part of the claimed design.
